UNITED STATES PATENT OFFICE

2,603,132

FINISHING MACHINE FOR CONCRETE SLABS

Arthur E. Miller, Milwaukee, Rudolph F. Lindow, Wauwatosa, and Samuel Shafer, Jr., Milwaukee, Wis., assignors to Chain Belt Company, Milwaukee, Wis., a corporation of Wisconsin

Application August 20, 1945, Serial No. 611,560

1 Claim. (Cl. 94—45)

1

The invention relates to machines for finishing concrete slabs, more particularly the slabs of concrete roads, and has for its primary object the provision of an improved apparatus for this purpose, of the type which travels along the forms defining the lateral limits of the slab, and employs a finishing member disposed longitudinally of the roadway and movable transversely back and forth between the forms to smooth or trowel the upper surface of the concrete mixture which has been deposited upon the road bed.

The advantages of the so-called "longitudinal" finishing machines for the finishing of concrete roads are well understood in the art, with perhaps the principal one being the tendency of finishing members so disposed to minimize or eliminate ridges or undulations extending transversely of the road and thus produce a smoother riding surface. The present invention provides a machine of this character which is a self-contained power driven unit comprising a frame arranged for travel upon the road forms and having a longitudinally disposed finishing member mounted thereon for rectilinear travel back and forth across the road with its under face in smoothing or troweling engagement with the upper surface of the plastic concrete which has been deposited on the subgrade between the forms (for example by a paving concrete mixer) and roughly brought to grade by manual or other means.

The finishing member is floatingly mounted for rising and falling movements relative to the main frame, and is guided in its traverse across the road by adjustable guides or templates whereby either flat or crown-surfaced slabs may be produced. A series of angularly disposed blades or vanes is provided at each side of the finishing member, which vanes are so positioned that those at the leading side of the finishing member engage and roughly level the slab surface just in advance of the finishing member, the angularity of the vanes being such as to tend to advance any excess mixture longitudinally of the road in the direction of travel of the machine on the forms, i. e. toward an unfinished portion of the slab. The angularity of the blades is reversible so as to preserve these movements when the direction of travel of the machine on the forms is reversed.

In one form, the finishing member in addition to being floatingly mounted as above mentioned, is pivoted for swinging movements about an axis transverse to its path of travel on the frame, whereby it may be canted to raise its leading edge and/or depress its trailing edge, to secure a better troweling effect; and means are provided for automatically reversing the tilt of the member as its direction of traverse across the road is reversed. This change of tilt is effected when-

2

ever the traverse is reversed, irrespective of whether the finishing member has reached its ultimate limit of travel at a form.

In another aspect, the finishing member while still floatingly mounted to enable it to produce either flat or crowned roads, is not arranged for the tilting movements just mentioned, but instead is equipped with a suitable vibrating device whereby rapid vibrations of relatively short amplitude may be imparted to the member and through it to the concrete. As will appear more fully below, the tilting form of finishing member may also be equipped with such a vibrating device, if desired.

15 A typical example of a machine embodying the above features is illustrated in the accompanying drawings forming a part of this specification, wherein:

Figure 1 is a top plan view of a preferred form of the machine;

Fig. 2 is a slightly enlarged transverse sectional view on approximately the plane indicated by the line 2—2 of Fig. 1, looking in the direction of the arrows;

Fig. 3 is an enlarged plan view of the finishing member and its associated parts, together with the carriage which supports the same for traverse on the main frame;

Fig. 4 is a vertical sectional view on approximately the planes indicated by the line 4—4 of Fig. 3, looking in the direction of the arrows;

Figs. 5 and 6 are vertical sectional views at right angles to Fig. 4, on the planes indicated by the lines 5—5 and 6—6 respectively in the latter figure, looking in the directions indicated by the arrows;

Fig. 7 is a view similar to Fig. 5, showing the modified form of the invention referred to above; and

Fig. 8 is a fragmentary sectional view, on approximately the plane indicated by the line 8—8 of Fig. 7.

Referring more particularly to Figs. 1—6, the machine comprises a substantially rectangular main frame 11 of a width sufficient to span the distance between the spaced parallel road forms 12 which are positioned and secured upon the prepared subgrade in the usual manner to define the lateral limits of the road slab. At its respective ends the frame 11 is preferably provided with extension frame structures 13 and 14 which are rigidly yet readily demountably secured to the main frame, and carry the transverse shafts 15 and 16 upon which are mounted the supporting wheels or rollers 17 and 18 disposed to rest upon the forms 12. The purpose of the frame extensions 13 and 14 is to secure a relatively long wheel base for the machine, whereby the effect of longitudinal inequalities in the forms may be minimized, while for purposes of

transport to and from a job, the extensions may be removed and the overall length of the machine thus materially reduced. At such times the wheels 17 and 18 are transferred from the shafts 15 and 16 to corresponding shafts 19 and 20 carried by the main frame 11, as indicated in broken lines at the right of Fig. 1.

An internal combustion engine or other appropriate motor is mounted in a housing 21 on the main frame 11, and drives a jack shaft 22 through a chain and sprocket drive 23. The said jack shaft in turn drives a pair of manually controllable reversing-gear and clutch mechanisms 24 and 25, the first of which drives the shaft 19 through bevel gearing 26, and the second of which drives a longitudinally disposed countershaft 27 through a chain and sprocket drive 28. When the frame extension 13 is in place its shaft 15 is driven from shaft 19 by a chain and sprocket drive 29, which of course is removed when the frame extension is demounted for transport of the machine.

The main frame 11 includes a pair of longitudinally spaced transversely extending channel members 30 which constitute rails for engagement by the supporting wheels 31 of a carriage 32 which supports the finishing member 33 and its associated parts. The said carriage is traversed on the rails 30, back and forth across the main frame, by a chain 34 driven by the countershaft 27. Adjacent each end of one of the rails 30, the main frame 11 carries a pivoted arm 35 having a roller 36 disposed to be engaged by a portion of the carriage 32 as the latter approaches the limit of its traverse. Each arm 35 is connected through linkage 37 to a snap-action device 38 associated with the reversing gear mechanism 25 and arranged to act upon the control lever 39 thereof to shift its clutches to reverse the direction of the drive from jack shaft 22 through the chain and sprocket drive 28 and countershaft 27 to carriage traverse chain 34. The direction of travel of the carriage 32 on rails 30 is thus automatically reversed at each end of the carriage traverse, although such reversal may be accomplished at any point across the road through manual operation of the reversing gear control lever 39.

The finishing member 33 comprises a channel disposed with its web downwardly and the under face of this web is preferably provided with a removable and renewable troweling plate or shoe 40. The finishing member and its associated parts are mounted on the carriage 32 as follows:

The carriage has secured to each of its ends a depending bracket or plate 41, to each of which is pivotally secured an upper pair of links 42 and a lower pair of links 43. Vertically disposed bars or arms 44 are pivotally connected as at 45 and 46 to the upper and lower sets of links respectively, and the lower ends of these bars are pivotally connected as at 47 to ears 48 and 49 rigidly carried by the finishing member 33. The ears 49 extend somewhat above the said member and are connected by a pin and slot connection 50 to the lower ends of the legs 51 of an inverted U-shaped lever 52, which legs are pivotally mounted on the pins 46 that connect the arms 44 to the links 43. The cross bar 53 of the said lever is provided with a lug 54 to which the carriage traversing chain is connected, as will be readily understood from Figs. 4 and 6. The said cross bar is also provided with a pair of upstanding projections 55 which are arranged to alternately

engage adjustable stops 56 and 57 carried by the frame of the carriage 32.

The motion of the chain 34 is thus transmitted to the carriage 32 through the lever 52 and the stops 56 and 57. When the motion of the chain is toward the right, as viewed in Fig. 6, it will swing the lever on its pivots 46 to engage the projections 55 with the stops 56 and thereby draw the carriage toward the right. At the same time the lever, through its pin and slot connections 50 with the ears 49 of the finishing member 33, will swing the latter on its pivots 47 to slightly elevate its then leading (right hand) edge and/or depress its trailing (left hand) edge. When the direction of chain travel is reversed, either automatically or manually as above described, the lever 52 will be swung over to engage the stops 57 thereby reversing the carriage travel, and at the same time the connections 50 will reverse the cant of the finishing member, all as will be readily understood from the drawings.

The lower end portions of the vertical arms 44 are provided with lateral extensions 58 to which are welded or otherwise rigidly secured the angle members 59, disposed one to either side of the finishing member 33. Each of these angles carries a plurality of longitudinally spaced bearings 60 which journal the pintles 61 (Fig. 3) of a series of angularly adjustable blades or vanes 62, the lower edges of which are positioned slightly above the plane of the lower face of the finishing member 33, see Figs. 5 and 6. Each pintle 61 rigidly carries an arm structure 63, the arms of each series being pivotally connected as at 64 to a longitudinal bar 65 whereby the arms, pintles and vanes may be actuated in unison. One pintle of each series is provided with an upward extension 66 which carries an arm 67, these arms being connected by a link 68 whereby the two series may be actuated simultaneously. One of the pintle extensions 66 is continued up to the top of the carriage 32, where it is provided with a hand wheel 69 or other appropriate means of actuation, whereby the angular settings of the blades 62 may be adjusted and/or reversed.

When the machine is moving forwardly on the forms, i. e. toward the right as viewed in Fig. 1, the blades 62 will be set substantially as shown in the drawings, at angles of approximately 45° to the line of travel. As will be understood from Figs. 5 and 6, the series of blades at the leading side of the finishing member 33 will engage and scrape off any high spots in the concrete and tend to move any such removed portions both laterally and forwardly of the road to fill in any low spots. Any excess not so used will be carried to the forms where it will be left, upon reversal of the carriage traverse, for manual removal. Mere reversal of the carriage travel from side to side of the road will not necessitate any re-setting of the vanes, but should the direction of travel of the machine longitudinally of the road be reversed, the angularity of the blades should be reversed, which may be accomplished through manipulation of the hand wheel 69.

The non-rigid or floating suspension of the finishing member and its associated parts just described, provided by the links 42 and 43, is for the purpose of accommodating vertical movements of these parts whereby the machine may operate on crowned roads. These movements are automatically accomplished as follows:

Forwardly and rearwardly of the carriage rails

30, the main frame 11 is provided with adjustable or warpable track or guide structures 70, spanning the frame from side to side. Each of these structures comprises a pair of vertically spaced flexible strips 71 and 72 the ends of which are seated in housings 73 carried by the frame 11. The upper strip 71 is welded or otherwise rigidly secured to a plurality of spaced brackets 74 which are provided with shelves 75 on which the lower strip 72 rests. Beneath each bracket is an adjusting screw 76 carried by a transverse member 77 of the main frame. As will be readily understood, particularly from Fig. 2, by adjusting these several screws the guide structures 70 may be warped to correspond to any degree of crowning of a road, from zero up to the maximum for which the machine is designed.

A vertical hanger bar 78 is rigidly secured to each vertical arm 44 in parallel relation thereto, the attachment in this instance being by means of a plurality of bolts or studs 79 surrounded by spacing sleeves 80. The lower ends of the bars 78 are pivotally attached at 81 to ears 82 secured to the finishing member 33, while the upper ends of the said bars carry rollers 83 disposed between the members 71 and 72 of the guide structures 70, and rolling on the members 72. These members thus support the finishing member and its associated parts, and with the structures 70 warped upwardly as shown in Fig. 2, as the carriage 32 is traversed back and forth on the rails 30, the said structures will cause the finishing member to gradually rise as it approaches the center of the road, and fall as it approaches the sides, according to the predetermined crown to be given the road.

The parallelogram mounting for the finishing member provided by the brackets 41, links 42 and 43, and the vertical arms 44, while accommodating the upward and downward movements of the finishing member, always preserves substantial perpendicularity of the said arms and prevents canting of the finishing member other than that intentionally provided by its pivotal mounting on its longitudinal axis and its connections with the swinging lever 52. Undue endwise movement of the member will be prevented by engagement of the suspending bars 78 with the adjacent frame members 71, as will be understood by reference to Fig. 4.

The operation of the machine will be clear from the foregoing, it being understood that it may be caused to travel along the forms 12 by the drive 23, 22, 24, 26, 19, 29 and 15, the direction of such travel being governed through manual shifting of the clutch devices of the reversing gear mechanism 24. During this travel the carriage 32 together with the finishing member 33 and blades or vanes 62 are traversed back and forth across the roadway with the finishing member in a tilted position which is automatically reversed with each reversal of the direction of carriage traverse. The mechanism should be so timed, of course, that the longitudinal travel during a traverse of the carriage in either direction is not greater than the length of the finishing member so as to insure working of all portions of the slab surface by the said member. During these movements the blades 62 roughly true up the surface just in advance of the finishing member by scraping off any high portions and moving them forwardly and laterally to fill in any low spots, with any excess being left at the side of the slab when the carriage reverses. If the longitudinal direction of travel of the machine be re-

versed, the angular set of the blades 62 is reversed by manipulation of the hand wheel 69, whereby to keep the excess material moving forwardly as regards the new direction of travel and thus prevent its being deposited on a surface which has just been worked over by the member 33.

In Figs. 7 and 8 there is illustrated a slight modification wherein the finishing member 33, instead of being pivotally attached to the vertical arms or bars 44 and 78 for canting movements whereby to elevate its leading edge, is rigidly attached to the lower ends of such arms, as by welding. In this case the said member carries one or more vibrating devices 84, of a conventional form, which may be driven through flexible shafting 85 from a motor 86 mounted on the carriage 32. The devices 84 impart rapid vibrations to the member 33 which tend to compact the concrete as well as aid in finishing its surface. To reduce the transmission of such vibrations to the main frame of the machine, pads 87 of rubber or like material may be interposed between the bracket shelves 75 and the supporting strip 72, and the rollers 83 may be provided with rubber or similar coverings 88, all as indicated in Fig. 8. Since the finishing member 33 is not canted, the lever 52 is omitted, and the chain 34 is attached directly to the carriage 32.

Obviously, the form of the invention shown in Figs. 1-6 may be equipped with vibrating devices similar to the devices 84, if so desired, as indicated in Fig. 2.

What is claimed is:

35 In a machine for finishing the surface of a concrete slab, the combination of a traversable frame provided with means for traversing the same; a carriage structure; means horizontally reciprocably mounting said carriage structure on the frame; an elongated finishing member having a flat concrete-engaging under surface, disposed longitudinally of the frame and longitudinally pivotally mounted by the carriage structure for tilting movements transversely of itself whereby to elevate its leading edge above its trailing edge; carriage-traversing mechanism mounted on the frame for reciprocating the carriage structure thereon; and a lever pivotally mounted by the carriage structure, having an arm connected to said carriage-traversing mechanism and being alternatively engageable with portions of the carriage structure whereby to transmit motion thereto from said traversing mechanism, said lever also having another arm connected to said finishing member eccentrically of the pivot of the latter, whereby reversals of said traversing mechanism will swing the finishing member about said pivot and alternately dispose its concrete-engaging surface in reverse angular relationships to the horizontal.
